CLAIM

The ornamental design for a microdermabrasion tool, as shown and described.

DESCRIPTION

FIG. 1 is an upper perspective view of a microdermabrasion tool;

FIG. 2 is a lower perspective view of the microdermabrasion tool shown in FIG. 1;

FIG. 3 is a front view of the microdermabrasion tool shown in FIG. 1;

FIG. 4 is a rear view of the microdermabrasion tool shown in FIG. 1;

FIG. 5 is a left-side view of the microdermabrasion tool shown in FIG. 1;

FIG. 6 is a right-side view of the microdermabrasion tool shown in FIG. 1;

FIG. 7 is a top view of the microdermabrasion tool shown in FIG. 1; and,

FIG. 8 is a bottom view of the microdermabrasion tool shown in FIG. 1.

The evenly spaced broken lines shown in the figures depict portions of the microdermabrasion tool that form no part of the claimed design. The dash-dot-dash broken lines depict boundaries of the claimed design, the dash-dot-dash broken lines form no part of the claimed design.
